ABSTRACT

Alkanolamides of this invention are made by condens-

ing a dicarboxylic acid of the following formula:

wherein x and y are integers from 3 to 9, x and y together equal 12, Z is a member of the group consisting of hydrogen and COOM_1 with one Z of each moiety, and M and M_1 are selected from the group consisting of hydrogen, sodium, potassium, lithium, and mixtures thereof, with either monoethanolamine, diethanolamine or isopropanolamine. The bisalkanolamides, dialkanolamides and monoalkanolamides formed at a ratio of 2:1 alkanolamine:carboxyl moiety are excellent detergents and wetting agents. The bisalkanolamides, dialkanolamides and monoalkanolamides of this invention made at a 1:1 ratio of alkanolamine-to-carboxyl moiety are used as foam, wetting and viscosity boosters. When small amounts of these alkanolamides are added to soaps, the formation of insoluble soaps in hard water is hindered and the resulting insoluble soaps are kept dispersed.

5 Claims, No Drawings

ALKANOLAMIDES OF DICARBOXYLIC ACID

BACKGROUND OF THE INVENTION

1. Field of the Invention

This invention relates to a class of bisalkanolamide, dialkanolamide and monoalkanolamide surface active agents. More particularly, this invention relates to bisalkanolamides, dialkanolamides and monoalkanolamides made from C_{21} -dicarboxylic acids; bisalkanolamides, dialkanolamides and monoalkanolamides made from blends of C_{21} -dicarboxylic acid with other fatty acids; and alkanolamides made from soaps of C_{21} -dicarboxylic acid blended with other fatty acids and fatty acid alkanolamides.

2. The Prior Art

The condensation products of carboxylic acids and either monoethanolamine, diethanolamine or isopropanolamine are generally referred to as alkanolamides. The condensation takes place according to reaction [1].

monoethanolamine

This reaction was discovered by Kritchevsky when diethanolamine and coconut fatty acids were reacted. It was found that if a mole ratio of 1:1 alkanolamine to fatty acid was employed, the product was insoluble in water. However, using a mole ratio of 2:1, alkanolamine to carboxyl moiety, a product quite soluble in water and possessing excellent wetting and detergency properties was produced. It was later determined that the insoluble 1:1 product was soluble in the presence of another detergent and that it significantly boosted the foaming, foam stability and detergency of the detergent to which it was added.

Although reaction [1] may appear to be straightforward, there are, in fact, two significant side reactions which occur:

These two reactions, [2] and [3], are due to the bifunctionality of the alkanolamine. It is possible by choosing the correct conditions to minimize reactions [2] and [3] and cause the predominant reaction to be [1]. In general, the lower the temperature consistent with a reasonable rate of amide formation, the less ester is formed. Any ester formed can be considerably reduced by heating the product with an alkali metal alkoxide, which tends to convert the esters to amides. The presence of esters is undesirable because of their deleterious effect on foaming. If a mechanical mixture of fatty alkanolamide and alkanolamine is formed, it does not possess the solubility and surface active properties of the product made by reacting two moles of alkanolamine and one mole of fatty acid. However, by merely heating the mechanical mixture at $120^\circ-140^\circ\text{C.}$, the properties of the 2:1 ratio of alkanolamide to fatty acid detergent are regained. The optimum detergency in the

2:1 products requires at least 5 percent alkanolamine soap to remain in the reaction mixture. An example of alkanolamides made from tall oil fatty acids is set forth in U. S. Pat. No. 2,744,888 to Carnes et al.

The applications of fatty acid alkanolamides are numerous, but the most important are foam boosting and stabilization, viscosity increasing, detergency, emulsification, increased wetting and lime-soap dispersion. The 2:1 products (alkanolamine:carboxyl moiety) are excellent detergents and wetting agents in their own right and are used as such in many products. However, the 1:1 products are normally used in conjunction with other detergents as detergency boosters. The addition of only 5 percent of a 1:1 alkanolamide to an alkyl aryl sulfonate-phosphate formulation boosts its detergency by 33%. Small amounts of alkanolamides added to soaps hinder the formation of insoluble soaps in hard water. Alkanolamides form excellent oil-in-water emulsions, and are therefore used extensively in cosmetic and pharmaceutical formulations. They also enhance the emulsifying properties of other emulsifiers such as ethylene oxide condensates of fatty acids. An important attribute of alkanolamides is their ability to increase the viscosity of other detergent formulations.

25 The reason for the great use of coconut fatty acids (lauric-myristic) as opposed to oleic types is by no means arbitrary. The fact is that optimum foam boosting properties for alkanolamides are found to be dependent on the number of carbon atoms in the fatty acid chain. Lauric is the most effective and the foam height drops off rapidly as the number of carbon atoms increase in the fatty chain.

30 It has been found that certain C_{21} -dicarboxylic acids may be reacted with alkanolamines to make bisalkanolamides, dialkanolamides and monoalkanolamides having good surface active properties. It is therefore the general object of this invention to provide novel bisalkanolamides, dialkanolamides and monoalkanolamides. It is another object of this invention to provide bisalkanolamides, dialkanolamides and monoalkanolamides from certain C_{21} -dicarboxylic acids. Another object of this invention is to provide alkanolamides from C_{21} -dicarboxylic acid soaps. Still another object of this invention is to provide novel bisalkanolamides, dialkanolamides and monoalkanolamides for blending with conventional alkanolamides to make detergents.

35 Other objects, features and advantages of this invention will become apparent from the following detailed description.

SUMMARY OF THE INVENTION

There is disclosed C_{21} -dicarboxylic acid bisalkanolamides, dialkanolamides and monoalkanolamides comprising a fatty acid compound of the following formula:

60 wherein x and y are integers from 3 to 9, x and y together equal 12, Z is a member of the group consisting of hydrogen and COOM_1 with one Z of each moiety, and M and M_1 are selected from the group consisting of hydrogen, sodium, potassium, lithium, and mix-

tures thereof, said fatty acid having been reacted with either monoethanolamine, diethanolamine or isopropanolamine. The C_{21} -dicarboxylic acid bisalkanolamides, dialkanolamides and monoalkanolamides may be mixed or blended with from about 5% to about 90% by weight of amides of a fatty acid selected from the group consisting of coconut, tallow, tall oil, soya, oleic, safflower and mixtures thereof. The bisalkanolamides formed at a 2:1 mole ratio of alkanolamine to carboxyl moiety have excellent surface active properties, and the bisalkanolamides made at a 1:1 mole ratio (alkanolamine:carboxyl moiety) are excellent detergent boosters.

DETAILED DESCRIPTION OF THE INVENTION

The essence of this invention is the discovery that when a mixture of predominately 5 carboxy-4-hexyl-2 cyclohexene-1-octanoic acid and 6 carboxy-4 hexyl-2 cyclohexene-1-octanoic acid is condensed with ethanolamine, diethanolamine or isopropanolamine, the bisalkanolamides, dialkanolamides and monoalkanolamides formed provide not only the advantages of a conventional alkanolamide, but also provides additional advantages such as, for instance, increased detergency. The mixture of these two isomers is represented by the general formula,

wherein x and y are integers from 3 to 9, x and y together equal 12, where Z is a member of the group consisting of hydrogen and COOM_1 with one Z of each moiety, and M and M_1 are hydrogen or are selected from various neutralizing agents. Although the isomers wherein x is 5 and y is 7 form a preponderance of the composition, there are minor amounts of the C_{21} -dicarboxylic acid where cyclohexene ring varies in position along the carbon chain. For the purpose of this specification, compositions of the general formulation shown above are termed " C_{21} -dicarboxylic acid soaps," and in the acid form are termed " C_{21} -dicarboxylic acid" or more simply " C_{21} -diacid."

The C_{21} -dicarboxylic acids used in this invention are produced from linoleic acid of various animal, vegetable and tall oil sources. The C_{21} -dicarboxylic acids may be made by reacting linoleic acid with acrylic acid and catalytic amounts of iodine. One such process for making the C_{21} -dicarboxylic acids for use in this invention is set forth in co-pending application, Ser. No. 159,070 filed July 2, 1971 now U.S. Pat. No. 3,734,859. When C_{21} -dicarboxylic acids are made from tall oil fatty acids according to the process in patent application Ser. No. 159,070, the reaction mixture is approximately 40% C_{21} -dicarboxylic acids and 60% oleic acid. The C_{21} -dicarboxylic acid alkanolamide may also be mixed with other fatty acid amides at from about 5 percent to 90 percent by weight. These amides include in addition to oleic acid those from coconut, tallow, soya, tall oil, safflower and mixtures thereof.

The method of preparing the bisalkanolamides dialkanolamides and monoalkanolamides of this invention comprises, in general, reacting the C_{21} -dicarboxylic

acid or a mixture of C_{21} -dicarboxylic acid and other fatty acid with an alkanolamine from the group consisting of monoethanolamine, diethanolamine or isopropanolamine at a mole ratio of from 1:1 to 2.2:1 alkanolamine to carboxyl moiety at temperatures sufficiently high to produce the condensation reaction to form the alkanolamide.

A preferred method of producing the bisalkanolamides of this invention is to mix a C_{21} -dicarboxylic acid 10 with monoethanolamine in equimolar quantity plus a small amount of excess alkanolamine, i.e., 3% to 10%, and heating this mixture to between 140°-200°C., preferably 150°-170°C. until the alkanolamide is formed, while removing the water of reaction.

15 The catalytic effect of sodium hydroxide in the preparation of bisalkanolamides of C_{21} -dicarboxylic acid from the dialkanolamines is critical, since without it, it was not possible to produce the bisalkanolamide. Sodium hydroxide is added to the condensation reaction 20 in an amount of 0.1 percent to 5 percent by weight of C_{21} -dicarboxylic acid and alkanolamine together, preferably 0.25 percent to 1.0 percent.

The alkanolamides of mono-soaps of C_{21} -dicarboxylic acid are generally either solids or very viscous liquids, but have one attribute not generally afforded by normal alkanolamides, water solubility. Of course, this solubility is due to the soap part of the molecule, but it may be a desirable characteristic in some 25 applications. For example, the use of this material as a self-contained detergent-lime soap dispersant system is one application.

The bisalkanolamides, dialkanolamides and monoalkanolamides of C_{21} -dicarboxylic acid find utility as 30 foam boosters, wetting improvers, viscosity increasers and lime soap dispersers. The physical and chemical characteristics of the C_{21} -dicarboxylic acid alkanolamides compared to oleic-type and other commercial alkanolamides appear in the Tables.

35 The C_{21} -dicarboxylic acids 1:1 bis-mono and bis-diethanolamides are both viscous liquids; whereas, the corresponding lauric-myristic-types are solids. This property is an advantage in applications where handling of solids is a problem. Since one of the main uses

40 for alkanolamides is in foam boosting, a study of this reaction was made utilizing the Ross-Miles procedure for measuring foam height and foam stability. The data shown gives indications of the foam boosting or lack thereof of the alkanolamides in the presence of as ethoxylated nonyl phenol. The C_{21} -dicarboxylic acid 1:1 bis-monoethanolamide is better at foam boosting and stabilization than the commercial lauric-myristic monoethanolamide. The Draves wetting test was used to

45 show improvement in wetting of a sulfated myristyl alcohol in a light-duty detergent formulation. The bisalkanolamides from C_{21} -dicarboxylic acid and alkanolamides from C_{21} -diacid 40%/oleic acid 60% mixtures gave good results when compared to the oleic-type alkanolamides. The monoethanolamide of the monosodium soap of C_{21} -dicarboxylic acid gave very good wetting properties. The lime soap disperser index may be

50 the key to using some of these materials in a phosphate-free detergent. The 1:1 bis-monoethanolamide of a mixture C_{21} -dicarboxylic acid and oleic acid (40%/60%) has excellent lime-soap dispersing powers. 55 The following examples are illustrative of the practice of this invention.

EXAMPLE 1

Preparation of Bis-monoethanolamide

Two commercially available fatty acids and two C_{21} -dicarboxylic acids were made into their respective bis-monoethanolamides and their properties compared. The reaction procedure for producing a 1:1 ratio of alkanolamine-to carboxyl moiety formation consisted of charging a reaction vessel with the fatty acid and an equimolecular quantity of monoethanolamine plus 10% excess. This mixture with continuous agitation, was heated at about 170°-175°C., under a nitrogen purge. The reaction was monitored by measuring the amount of water produced and the acid number of the reaction mixture. The reaction was stopped when the acid number dropped below 5.

Following the same procedure, bis-monoethanolamides were prepared at a ratio of 2:1

ties compared. Both 1:1 diethanolamine-to-carboxyl moiety ratio and 2:1 diethanolamine-to carboxyl moiety ratio amides were prepared. The reaction vessel was charged with the fatty acid and proper amounts of diethanolamine plus about 5% excess amine. To the reaction mixture 0.25% by weight of the mixture of solid sodium hydroxide was added to catalyze the reaction. The reaction mixture was continuously stirred while heated at about 170°-175°C. The rate of reaction remained constant until almost all of the theoretical amount of water had been removed. The resulting product was estimated by IR to be over 75% bis-diethanolamide. There was some ester in the product; however, by aging the material at 60°C. for several days, considerable reduction in ester content was achieved with a corresponding increase in bis-diethanolamide. The physical and chemical characteristics of the bis-diethanolamides are given in Table II.

monoethanolamine to carboxyl moiety. Physical and chemical characteristics of the bis-monoethanolamides are shown in Table I.

The amide content of the alkanolamides is difficult to determine chemically due to the presence of amide-esters and ester-amines. However, IR spectrophotometry was used with some success with the lauric-type amides. A pure sample of C_{21} -dicarboxylic acid, bis-monoethanolamide was isolated by column chromatography. Using this material as a standard, an estimate of the amide content of a C_{21} -dicarboxylic acid, and mixture of C_{21} -diacid (40 percent) and oleic acid (60 percent) alkanolamide was made. This was about 80 percent.

35 EXAMPLE 3
Preparation of Alkanolamides of Mono-soaps of C_{21} -Dicarboxylic Acid

These alkanolamides were prepared as follows: 200 gram fatty acid samples of C_{21} -dicarboxylic acid, were each half neutralized with 50% sodium hydroxide solutions. The fatty acids were heated to approximately 40 110°C. and held there for about one hour or until clear and homogeneous. The remaining acidity was then neutralized when monoethanolamine or diethanolamine were added, including a slight excess, i.e., 10%. 45 The mixture was then heated to 170°-175°C. under nitrogen. The water of reaction was collected. When the

EXAMPLE 2
Preparation of Bis-diethanolamides

As in Example 1, two commercially available fatty acids and two C_{21} -dicarboxylic acids were made into 65 their respective bis-diethanolamides and their proper-

theoretical amount of water had been removed (water added with caustic plus water from salt formation plus water from alkanol amide formation) the reaction was terminated. The products were generally soluble or dispersible in water. The physical and chemical characteristics are given in Table III.

EXAMPLE 4

This example illustrates the preparation of the alkanolamide of a C_{21} -dicarboxylic acid 40%/oleic acid 60% mixture. The fatty acid mixture (200 grams) was half neutralized with 50% sodium hydroxide and heated at 110°C. until clear. The remaining acidity was neutralized by the addition of a molar amount of monoethanolamine including a slight excess. The mixture was then heated to 170° – 175°C. under nitrogen and the water of the reaction collected. The reaction was terminated when the theoretical amount of water had been removed. The chemical and physical properties are shown in Table IV.

EXAMPLE 5

This example illustrates the ability of the bisalkanolamides and alkanolamide soaps to disperse the insoluble calcium or magnesium soap of oleic acid. The procedure used to determine this value was the method of Borghetty and Bergman which is:

% Lime Soap Disposing Powder = grams of dispersing agent to disperse soap $\times$ 100/weight of sodium oleate

The results are given in Table V for the bisalkanolamides and the alkanolamide soaps from Examples 1–4.

35 time required to wet a standard cotton skein at a particular temperature and a standard concentration of wetting agent. The weighed cotton skein is immersed in the wetting solution in a graduate cylinder and the time required to cause the cotton stirrup connecting the skein to the weight to relax is recorded as the sinking time. The temperatures employed in this test were 25°C. and 40 50°C. and the concentration of wetting agent in a standard light-duty detergent formulation was 0.1 and 0.25%. The cotton skeins were 5.00 grams and the hooks used were fabricated out of No. 10 copper wire and were made to weigh exactly 3.00 grams each. The results for the bisalkanolamides are given in Table VI.

The light duty detergent formulation from which the wetting solutions were prepared was as follows.

- 2.5 grams amide
 50 12.5 grams sodium tetradecyl sulfate
 7.5 grams isopropyl alcohol
 27.5 grams water
- 10 The 0.1 and 0.25% figures represent the sum of the alkanolamide plus the sodium tetradecyl sulfate.
- 25 55 Foam height and stability of the bisalkanolamides of the invention were compared to the alkanolamides from commercial fatty acids according to the Ross-Miles test. The tests were run on the bisalkanolamides, bis-dialkanolamides and alkanolamide soaps made in 45 60 Examples 1–4. The test was carried out using a 20:80 mixture (amide:surfactant) with an ethoxylated nonyl phenol (Igepal C030). The results for both the acids

Notes: a Distilled disproportionated tall oil fatty acid (C₁₈); *Ins. = Insoluble.

While the invention has been described and illustrated herein by references to various specific materials, procedures and examples, it is understood that the invention is not restricted to the particular materials, combinations of materials, and procedures selected for that purpose. Numerous variations of such details can be employed, as will be appreciated by those skilled in the art.

Having thus described the invention, what is claimed is:

1. An alkanolamide consisting essentially of the condensation product resulting from heating together at temperatures between 140°C-200°C,

  - a. an alkanolamine selected from the group consisting of monoethanolamine, diethanolamine and isopropanolamine,
  - b. with a mixture of dicarboxylic acids having the formula:

wherein x and y are integers from 3 to 9, x and y together equal 12, where one Z is a hydrogen (H) and the other Z is a carboxylic acid group (COOH) said ratio of alkanolamine to carboxyl group being 2:1 to 1:1.

2. The bisalkanolamide according to claim 1 wherein the mole ratio of alkanolamine to dicarboxylic acid is

3. The product of claim 1 wherein the alkanolamine is monoethanolamine and the temperature is between 150° and 170°C.

4. The product of claim 1 wherein said alkanolamine is diethanolamine, said temperature is between 150° and 170°C., and sodium hydroxide is present in an amount of between 0.1% and 5.0% by weight of said dicarboxylic acid and amine.

5. A composition consisting essentially of:

- A. A bisalkanolamide consisting essentially of the condensation product resulting from heating together at temperatures between 140°C–200°C, an alkanolamine selected from the group consisting of monoethanolamine, diethanolamine, and isopropanolamine, with a mixture of dicarboxylic acid having the formula,

wherein x and y are integers from 3 to 9, x and y together equal 12, where one Z is a hydrogen and the other Z is a carboxylic acid group, said ratio of alkanol-amine to carboxyl group being 2:1 to 1:1; and

- B. An amide of a fatty acid selected from the group consisting of coconut, tallow, tall oil, soya, oleic, safflower and mixtures thereof, said composition comprising from about 5 to 90% by weight (A) and from 10% to 95% by weight of (B).
